UNITED STATES PATENT OFFICE

ADOLPH W. RYBECK, OF MILWAUKEE, WISCONSIN, ASSIGNOR TO T. L. SMITH COMPANY,
OF MILWAUKEE, WISCONSIN, A CORPORATION OF WISCONSIN

CONCRETE-MIXING MACHINE

Application filed November 22, 1929. Serial No. 409,018.

This invention relates to certain new and useful improvements in concrete mixers especially adapted for street paving and refers more particularly to their discharge buckets.

5 The discharge buckets of machines of this type usually travel along a horizontal boom to facilitate spreading of the concrete, and in the past difficulty has been experienced in properly discharging the contents of the buckets.

10 It is therefore an object of this invention to provide a discharge bucket of this character, so constructed as to impart a motion to the material therein during discharging, whereby a positive and quick discharge of material is obtained.

15 Another object of this invention resides in the provision of a discharge bucket of the character described which is so constructed as to have a greater discharge angle.

20 And a further object of this invention is to generally simplify and improve the construction of such buckets.

With the above and other objects in view 25 which will appear as the description proceeds, my invention resides in the novel construction, combination and arrangement of parts substantially as hereinafter described and more particularly defined by the appended 30 claims, it being understood that such changes in the precise embodiment of the herein disclosed invention may be made as come within the scope of the claims.

35 In the accompanying drawings, I have illustrated one complete example of the physical embodiment of my invention constructed according to the best mode I have so far devised for the practical application of the principles thereof, and in which:

40 Figure 1 is an elevational view of a portion of a concrete mixing machine of the "paver" type embodying my invention and having parts broken away to illustrate structural details; and

45 Figure 2 is a perspective view of the discharge bucket per se.

Referring now more particularly to the accompanying drawings, the numeral 5 designates the frame of a concrete mixing machine 50 particularly adapted for street paving and

portably mounted upon a caterpillar traction mechanism 6. The usual mixing drum 7 is mounted upon the frame 5 and is arranged to discharge its contents into a discharge bucket 8, through a chute 9.

55

The discharge bucket 8 is suspended from a carriage 10, which is movable along a boom 11 swingingly mounted at its inner end from a suitable bearing 12 and supported at its outer end by means of a cable 13. The cable 60 is secured to the boom as at 14 and is trained about a sheave 15 freely rotatably mounted from a bearing member 16 at the upper end of the frame 5, passed about a second sheave 17, carried by the boom, and then over a third 65 sheave adjacent the sheave 15, and not shown, to be connected with and wound about a drum 18 carried by the boom. As is customary, the drum 18 enables the boom to be adjusted vertically, and to swing the same about its pivotal 70 mounting, a handwheel 19, is provided to be grasped by an operator stationed upon a platform 20.

The boom preferably consists of a pair of spaced channel irons arranged with their 75 flanges outwardly, and the carriage 10 is provided with spaced arms projected upwardly on opposite sides of the boom to mount rollers 21 which track upon the lower flanges of the channel irons. The lower portions of the carriage sides have plates 22 riveted or otherwise secured thereto, to which the bucket 8 is secured.

The bucket 8, as best illustrated in Figure 2, comprises a stationary section 23 consisting of a substantially vertical forward wall 24, side walls 25, to which the plates 22 are secured, and a bottom 26 disposed at an angle to the vertical forward wall 24. The edges of the side walls 25 are also directed at an 85 angle and are strengthened by angle irons 27 riveted thereto. The upper ends of the angle irons 27 have bearing members 28 fixed thereto, to which the movable section 29 of the bucket is pivotally connected by pins 30.

95

The movable section 29 consists of an arcuate rear wall 31, side walls 32 and a bottom 33 also disposed at an angle so that when the sections are closed onto each other the bottoms 33 and 26 come together and form 100

the apexes of an angle slightly more than 90 degrees. Inasmuch as the side walls 32 are received between the side walls 25 and are of such size as to lap over the edges of the walls 25, when closed, it is evident that when the movable section is in closed position leakage of material is prevented. It is also noted that the bottom 33 has considerably more area than the bottom 26 so that the 10 majority of the material is disposed over the bottom 33, which being movable, with the movable section, facilitates the discharge of material.

The means for closing and maintaining the movable section closed consists of a lever 34, formed by a pair of spaced links having one end pivotally connected with a flange 35 secured to the bottom 26 of the stationary section and having their other end portions 20 connected with the bottom 33 of the movable section by a chain 36. The bottom 33 of the movable section is preferably strengthened by a channel iron cross piece 37 at its point in connection with the chain 36.

It will thus be seen that upward movement 25 of the free end of the lever 34 draws the chain taut and closes the movable section, and to obtain this movement of the lever its free end is connected with a lever 38 fixed to a shaft 39 journalled at its ends in bearings 40 carried by the sides of the carriage 10. The means connecting the levers 34 and 38 consist of an arcuate link 41 having one end pivotally connected with the outer end of the lever 38 and its other end connected with the free end of the lever 34 through a link mechanism 42 which embodies shock absorbing springs 43.

Also fixed to the shaft 39 is a lever 44 carrying at its outer end a roller 45 and a hand grip 46. The grip 46 facilitates manual actuation of the shaft 39 to open and close the movable section. When the movable section is in closed position, as best illustrated in full lines in Figure 1, the axis of the pivotal connection of the lever 38 with the link 41 moves beyond an imaginary line drawn through the centers of the shaft 39 and the connection of the link 42 with the outer free end of the lever 34. Movement of the lever 38 when in this position is restrained by a movable stop 47 normally held against the inner end of a bearing 48 forming part of the carriage 10.

The movable stop 47 is maintained in its position engaging the bearing 48 by an expansive spring 49, coiled about a shaft 50 extended from the stop and slidably in the bearing 48, and confined between the outer end of the bearing and lock nuts 51 threaded on the outer end of the shaft 50. As stated the axis of the connection between the lever 38 and the link 41 is beyond dead center when the lever 38 engages the stop 47 so that the movable section is held closed and may be

opened by merely moving the lever 38 to the other side of dead center.

In operation, the bucket 8 after having been filled with concrete is carried outwardly along the boom 11 to the place at which it is 70 desired to discharge its contents, and then by means to be described, it is tripped and discharged. The means for carrying the bucket outwardly along the boom is of conventional construction and embodies a cable 75 52 having one end connected in any suitable manner with the carriage and being trained about an idler sheave 53 at the outer end of the boom. From the sheave 53 the cable extends rearwardly and is trained over a 80 sheave 54 adjacent the inner end of the boom with its periphery in substantial alignment with the axis about which the boom swings, and from it extends upwardly through the center of the bearing 12 to be trained about another idler sheave 55, and then is brought 85 downwardly in the customary manner to be wound about a suitable drum, not shown.

After the bucket 8 reaches its desired position along the boom the operator disconnects the drive from its respective drum and causes a second drum, not shown, to wind up a retrieving cable 56 to effect the return of the bucket. The outer end of the retrieving cable 56 is connected with the stop 47 as at 90 57 and upon inward movement of the cable the tension of the spring 51 is overcome and the stop 47 is moved inwardly carrying the lever 38 to the other side of its dead center and releasing the movable section of the 95 bucket for opening by the weight of material therein. It is noted that inasmuch as the majority of the contents are disposed above the movable section bottom the material will be given a certain motion in opening which 100 will insure its immediate and complete discharge.

The retrieving cable 56 like the cable 52 is trained about a sheave rotatable about the axis of the sheave 54 to also extend upwardly 110 through the bearing 12 and be trained about a sheave 58 adjacent the sheave 55 from where it extends downwardly to be wound about its respective drum. As the bucket is returned upon retrieving the cable 56 it remains in open position until the roller 45 carried by the lever 44, engages a shoe or cam 59 fixed to a cross bar 60 of the boom. As the roller 45 engages the cam 59 it is forced 115 downwardly rotating the shaft 39 in a 120 counterclockwise direction and thus drawing the movable section to closed position.

From the foregoing description taken in connection with the accompanying drawings, it will be readily apparent to those 125 skilled in the art to which an invention of the character described appertains, that I provide an improved construction for discharge buckets of concrete mixing machines wherein the complete and immediate dis- 130

charge of its contents is assured and in which novel means are provided for opening and closing the same.

What I claim as my invention is:

5 1. In a device of the character described, a discharge bucket comprising cooperating sections of substantially the same cubical content, means hingedly connecting the sections at their tops whereby one section is movable with respect to the other, and means 10 releasably maintaining said section engaged with the other section to close the bucket, said means comprising a lever connected with said second mentioned section, flexible means connecting the lever with the movable section, and means for moving the lever.

20 2. A bucket of the character described, comprising cooperating sections, means hingedly connecting the sections whereby one is movable with respect to the other, means 25 for maintaining the movable section engaged with the other section, said means including a lever connected with the second mentioned section, means connecting the lever with the movable section, means for drawing the lever away from the movable section, and means whereby said last mentioned means moves beyond dead center to releasably maintain the movable section in closed 30 position.

35 3. A bucket of the character described, comprising cooperating sections, means hingedly connecting the sections adjacent their tops, whereby one section is movable 40 with respect to the other, means for maintaining the movable section in engagement with the other to close the bucket, said means including a lever pivotally connected with the second section, means connecting the lever with the movable section and an operating lever swingingly mounted, means connecting the lever with the operating lever, and means 45 for moving the operating lever to a point at which its connection with the means connecting it with the first mentioned lever passes beyond dead center to releasably maintain the movable section closed.

50 4. A bucket of the character described, comprising cooperating sections, means hingedly connecting the sections adjacent their tops, whereby one section is movable 55 with respect to the other, means for maintaining the movable section in engagement with the other to close the bucket, said means including a lever pivotally connected with the second section, means connecting the lever with the movable section, an operating lever swingingly mounted, means connecting the lever with the operating lever, means for 60 moving the operating lever to a point at which its connection with the means connecting it with the first mentioned lever passes beyond dead center to releasably maintain the movable section closed, and means for moving the operating lever to the other side of dead

center to release the movable section for opening.

5 5. In a device of the character described, a discharge bucket comprising cooperating sections, means hingedly connecting the sections adjacent their tops whereby one section is movable with respect to the other, and means releasably maintaining said sections engaged with each other to close the bucket, said means comprising a lever connected with one section, flexible means connecting the lever with the other section, and means for moving the lever.

In testimony whereof I have hereunto affixed my signature.

ADOLPH W. RYBECK.
